UNITED STATES PATENT OFFICE.

JAMES H. ASSELIN, OF SAN FRANCISCO, CALIFORNIA.

TONGUE SWITCH AND MATE FOR RAILWAYS.

Application filed August 9, 1922. Serial No. 580,800.

To all whom it may concern:

Be it known, that I, JAMES H. ASSELIN, a citizen of the United States, residing at the city and county of San Francisco and State of California, have invented new and useful Improvements in Tongue Switches and Mates for Railways, of which the following is a specification.

This invention relates to a tongue switch and mate for railways, and especially to that type employed in electric street railway service and the like.

The object of the present invention is to generally improve and simplify switches and mates of the character described; to provide a switch which may be attached to a through rail and which may be placed on the inside or outside rail according to the nature of the curve on which it is used; to do away with switches constructed of cast steel castings, such as are now used in all street railway switches by substituting a cast iron casting which may be attached directly to a through rail to eliminate three of the four joints now required in connection with all street railway switches; to eliminate all four pair of switch plates that are now required on all street railway switches; to do away with all cable bonds as the switch forming the subject matter of this application is attached or secured directly to a through rail; to practically eliminate the replacement of switch tongues; to materially reduce the cost of maintenance in connection with switches, and further to relieve the switch tongues of practically all wear as the tongues will only be used when rounding curves; to provide a mate for the switch forming the subject matter of this application which will do away with the cast steel special mate now employed on street railways; to provide a mate which may be attached to a through rail; to eliminate all but one fish plate; to do away with cable bonds in connection with the mates; to provide a mate which is raised so that the car wheel will flange ride, thus protecting the point of the mate; to reduce the cost of maintenance by lessening replacements due to the small amount of wear and tear encountered, and also due to the fact that the major number of joints is practically done away with. Further to provide a switch and mate which may be applied to any size high T-

rail or a standard T-rail, and which may be 55 adapted to any radius or curve required. Other objects will hereinafter appear.

One form of structure which the switch and mate may assume is exemplified in the following description and illustrated in the 60 accompanying drawings, in which—

Figs. 1 and 2 are plan views of the switch and mate respectively which are employed where the major portion of the traffic, whether inbound or outgoing, is carried by 65 the through rails.

Fig. 3 is a cross section on line A—A, Fig. 1.

Fig. 4 is a cross section on line B—B, Fig. 1.

Fig. 5 is a cross section on line C—C, Fig. 1.

Fig. 6 is a cross section on line D—D, Fig. 1.

Fig. 7 is a cross section on line E—E, 75 Fig. 1.

Fig. 8 is a cross section on line F—F, Fig. 2.

Fig. 9 is a cross section on line G—G, Fig. 2.

Fig. 10 is a cross section on line H—H, Fig. 2.

Fig. 11 is a cross section on line I—I, Fig. 2.

Fig. 12 is a cross section on line J—J, 85 Fig. 2.

Figs. 13 and 14 are perspective views of the switch and mate respectively illustrated in Figs. 1 and 2.

Fig. 15 is a perspective view of the switch 90 tongue illustrated in Figs. 1 and 13.

Figs. 16 and 17 are plan views of the type of switch and mate which are employed where the major portion of the traffic, whether inbound or outgoing, is switched 95 off the through tracks.

Fig. 18 is a cross section on line I'—I', Fig. 16.

Fig. 19 is a cross section on line D' D', 100 Fig. 17.

Fig. 20 is a cross section on line K—K, Fig. 17.

Figs. 21 and 22 are perspective views of the switch and mate respectively illustrated in Figs. 16 and 17.

Referring to the drawings in detail, and particularly to sheets 1 and 2, L indicates the switch and M the mate, which are employed

where the major portion of the traffic is carried by the through rails indicated at 2 and 3.

For the purpose of clearly explaining the invention, a detailed description of the switch will first be given, and secondly a detailed description of the mate. The switch consists of a cast iron casting about eight feet long. This casting is indicated at 4, see Figs. 4, 5, 6 and 7, and it is fastened to the through rail 2 by a suitable number of bolts 5 as illustrated in Fig. 13. The casting consists of a base portion which is flanged as at 7, a main body portion as indicated at 4, and an upper flanged guard 8. The upper surface of the main body portion 4 is flat and is preferably machined to form a supporting surface for a switch tongue generally indicated at 9. The switch tongue 20 is made of forged or manganese steel and the heel of the tongue is pivotally attached to the casting or the main body portion 4 by means of a pin 10, which is journalled in a removable brass bushing 11. The casting 25 tapers from end to end, being heaviest at the heel portion of the switch and lightest at the point of the switch. The flange 8 cooperates at one end with the flange 12 of the through rail 2 and at the opposite end 30 with a flange 13 of the curved rail 14. No joint is formed between the through rail 2 and the casting which supports the switch as this casting is directly secured to the side of the rail and only one 35 joint is therefore required and that is the joint which is formed between the casting and the curved rail 14 and which is illustrated at 15. A spacing block 16 is introduced at this point and is perhaps best illustrated in Figs. 1, 3 and 13, said spacing block being secured by the bolts 5^a. These 40 bolts also serve the function of securing the curved rail 14 with relation to the through rail 2 and the casting. The switch tongue proper may be manually operated or mechanically operated as desired. If it is 45 mechanically operated a lug 17 is employed which projects downwardly into a cross slot 18, see Fig. 1, formed in the upper surface of the body portion 4. A connection is then made in any suitable manner between the mechanically actuating mechanism and the lug 17, but as this matter is of no particular importance in the present instance, 50 further illustration thereof has been eliminated.

The mate illustrated at M consists of a steel casting approximately seven feet in length. This is bolted as illustrated in Fig. 14 to the curved rail 19, which in this instance is the continuous rail, the through rails being the rails indicated at 2 and 3 and are the rails which carry the major portion of the traffic. A cast iron filler, such as illustrated at 16^a, see Figs. 1, 8 and 14, is em-

ployed and this filler is secured to the rail 19 by means of bolts 20 which also secure the through rail 3 with relation to the casting of the mate M and the rail 19.

The grooves in the mate illustrated in Figs. 9, 10, 11 and 12 are raised so that the car wheel will flange ride, thus protecting the point of the mate. The mate constructed as here shown does away with the cast steel special mate now used by street railways. It eliminates all but one fish plate. It does away with all cable bonds. It does away with all but one joint. It is raised so that the car wheels will flange ride. It is directly attached to the side of a rail and as such does not only cut down the original cost and price of installation, but maintenance charges are also lessened due to the fact that hammering, wear and tear are practically eliminated. This is also true of the switch as the switch does away with a steel casting such as is now used on all street railways, that is a cast iron casting is substituted which is attached directly to a through rail. It eliminates three of four joints that are now usually required on all street railways. It eliminates four pair of fish plates commonly required. It does away with all cable bonds as the switch is attached directly to the through rail. It practically eliminates the replacement of switch tongues as the major portion of the traffic is carried by the ball of the through rail, and as practically all joints are eliminated maintenance cost is reduced to a minimum. The first purchase price and installation are also reduced, and as the casting proper is not subjected to wear of any consequence it may be removed and re-used when the through rails are worn. It should further be noted that no load is thrown on the switch tongue, except when a car rounds a curve and as such the wear of the switch tongue should be very small.

The switch and mate illustrated in Figs. 16, 17, 21 and 22 are as previously stated employed where the major portion of the traffic is side tracked or travels over the curved rails indicated at 30 and 31, this being true whether the traffic is inbound or outgoing. The castings employed in each instance are, practically speaking, identical to those illustrated in Figs. 1 and 2. This can be seen if comparison is made between Figs. 18 and 19 and Figs. 6 and 11, as these figures are cross sections taken at the same points of the switches and mates respectively.

In connection with the switch shown in Fig. 17, it may be stated that a steel plate is employed at the point of the switch as indicated at 35. (See also Fig. 20.) This is employed for the purpose of taking the flange thrust when the traffic is travelling in the direction of arrow a. If this portion were made of cast iron, it could readily be seen that it would rapidly wear away and the

flange guard would be destroyed. This steel plate is also illustrated in Fig. 22 and it is secured to the side of the rail and the casting by means of bolts 36, see Fig. 22.

5. In conclusion we will state that there are two forms of mates employed, one being used on the inside rail and the outside rail, their position depending entirely upon the proportion of traffic carried. On the inside mate 10 the groove is partially used so as to hold the wheel on the curve until the switch is passed, and on the outside mate the groove is eliminated and more flange clearance is given to allow the wheel to take the curve.

15. The switch and mate illustrated in the several drawings can be manufactured for any size high T-rail or for a standard T-rail, and for any radius or curve. The cost of manufacture of both the tongue switch and the 20 mate is very low when comparison is made with the standard forms of switches and mates now commonly used by all street railways. The cost of installation is considerably lessened. All joints, except one, are 25 eliminated, and when it is also considered that only the minor portion of the traffic is carried by the movable switch tongue, it can readily be seen that wear and tear will be reduced to a minimum and maintenance cost 30 will be reduced proportionately.

Having thus described my invention, what I claim and desire to secure by Letters Patent is—

1. The combination with the straight and 35 the curved rail of a switch one of the rails having a continuous ball portion, of a switch casting adapted to be secured to the side of the rail, which carries the major portion of the traffic, and a switch tongue directly supported by said casting, the heel of said 40 tongue aligning with the ball of the rail which carries the minimum portion of the traffic.

2. In a switch of the character described 45 the combination with the straight and the curved rail, and one of said rails being a continuous rail and having a continuous ball portion, of a switch casting adapted to be secured to the inside of the continuous rail, and a switch tongue supported entirely by 50 the casting and having its heel end aligning with the ball of the other rail.

3. In a switch of the character described 55 the combination with the straight and the curved rail, and one of said rails being a continuous rail and having a continuous ball portion, of a switch casting adapted to be secured to the inside of the continuous rail, and a movable switch tongue supported entirely by the casting and having its heel end disposed in alignment with the ball of the 60 other rail.

4. In a switch of the character described, the combination with the straight and the

curved rail, and one of said rails being a 65 continuous through rail and having a continuous ball portion, of a casting secured to the inside of the continuous rail, and a tongue supported by the casting and normally aligning with the ball of the other 70 rail.

5. In a switch of the character described, a pair of straight and a pair of curved rails, one rail of each pair being a continuous through rail and having a continuous ball 75 portion, a casting secured to each continuous rail, and a tongue supported by each casting, the heel of each tongue being placed in alignment with the other rails.

6. In a switch of the character described, 80 a pair of straight and a pair of curved rails, one rail of each pair being a continuous through rail and having a continuous ball portion, a casting secured to each continuous rail, a movable switch tongue supported by 85 one casting, and a stationary tongue supported by the other casting, the heels of said tongues aligning with the other rails.

7. In a switch of the character described 90 a straight rail having a continuous ball portion, a curved rail, a switch casting secured to the inside of the straight rail, and a movable switch tongue supported by said casting, the heel of said tongue aligning with 95 the ball of the curved rail.

8. In a switch of the character described, a continuous curved rail having a continuous ball portion, a straight rail, a switch mate casting secured to the inside of the curved rail, and a tongue supported by said casting 100 and aligning with the ball of the straight rail.

9. In a switch of the character described, a continuous curved rail having a continuous ball portion, a straight rail, a switch mate casting secured to the inside of the curved rail, a tongue supported by said casting and aligning with the ball of the straight rail, a filler block disposed between the straight rail and the curved rail, and means for securing the straight rail to the filler block 105 and the curved rail.

10. In a switch of the character described 110 a straight rail having a continuous ball portion, a switch casting secured to the inside of the rail, a curved rail abutting one end of said casting, a filler block disposed between the straight rail and the end of the curved rail, bolts passing through the straight rail, the filler block and the end of the curved rail to secure the same as a unit, and a switch tongue supported by the casting, said switch tongue being pivotally connected to the casting and having its heel portion disposed in alignment with the ball of 115 the curved rail.

JAMES H. ASSELIN.
